GAVEL

Arthur F. Cervenka, Vanderbilt Blvd., Oakdale, N.Y.

Filed Nov. 24, 1961, Ser. No. 67,671

Term of patent 14 years

(Cl. D34—5)

FIG. 1

FIG. 2

FIG. 3

FIG. 1 is an edge view of my gavel, showing my new design;

FIG. 2 is a plan view thereof, the side opposite thereto being substantially the same; and

FIG. 3 is a perspective view.

The characteristic feature of my design resides in the combination of a flat gavel having a row of ornamentation on each side of the head portion and a plurality of rows of ornamentation about the neck of the handle, all as shown.

I claim:

The ornamental design for a gavel, substantially as shown and described.
